(**) Term: **14 Years**

(57) **CLAIM**

(21) Appl. No.: **29/229,787**

The ornamental design for a light emitting diode lamp, as shown and described.

(22) Filed: **May 12, 2005**

DESCRIPTION

(51) **LOC (8) Cl.** 13-03

FIG. 1 shows a front view of the light emitting diode lamp which incorporates the design of the present invention.

(52) **U.S. Cl.** D13/180

FIG. 2 shows a top view of the light emitting diode lamp of FIG. 1.

(58) **Field of Classification Search** D13/180;
D26/2; 257/79, 80, 81, 82, 88, 89, 95, 98,
257/99, 100, 678, 680, 433, 434; 313/483,
313/498, 500; 361/820; 362/555, 800

FIG. 3 shows a bottom view of the light emitting diode lamp of FIG. 1.

See application file for complete search history.

FIG. 4 shows a right side view of the light emitting diode lamp of FIG. 1.

FIG. 5 shows a left side view of the light emitting diode lamp of FIG. 1.

OTHER PUBLICATIONS

FIG. 6 shows a cross sectional view along line VI—VI shown in FIG. 2 of the light emitting diode lamp of FIG. 1.

U.S. Appl. No. 29/229,788, filed May 12, 2005, Teshima.

FIG. 7 shows a cross sectional view along line VII—VII shown in FIG. 2 of the light emitting diode lamp of FIG. 1; and,

U.S. Appl. No. 29/229,789, filed May 12, 2005, Teshima.

FIG. 8 shows a perspective view of the light emitting diode lamp.
